TUBE STRAIGHTENING MACHINE

Clarence L. Dewey, Elkhart, Ind.

Application February 6, 1943, Serial No. 474,923

5 Claims. (Cl. 153—54)

The machine of the present invention is designed primarily to straighten the walls of cylindrical tubing and remove therefrom any slight bends, kinks, or inequalities therein and to give exact and substantially-uniform circularity to the tube wall throughout. As incidental and preliminary to the tube straightening operation I have found that it is highly desirable to subject the tube to a slight reducing operation in the manner hereinafter described, in order to rework the metallic structure of the tube wall sufficiently to remove any previous set of fibers therein so that when the tube is finally straightened, there will be no tendency for the tube walls to restore to their previous condition of inequality, thereby producing a tube of increased strength due to the reworking of the metal and one which will be smooth, even, and uniform and to have exact circularity at all points.

The invention further consists in the means provided for the mounting and driving of the combined reducing and straightening rolls and to the general construction of the machine as a whole and the constituent parts thereof.

In the drawings illustrating the invention,

Figure 1 is a left-hand end view of a machine embodying four rolls of uniform construction arranged in radial relation to the tube and driven from a common source of power;

Fig. 2 is a longitudinal view partly in section taken on the off-set line 2—2 of Fig. 1;

Fig. 3 is an enlarged longitudinal sectional view taken on line 3—3 of Fig. 1; and

Fig. 4 is a cross-sectional view taken on the off-set line 4—4 of Fig. 3.

The machine as a whole is mounted upon a base frame 10 which carries a left end frame plate 11 and a similarly spaced right end plate, not shown, which plates in unison provide a mounting for the opposite ends of a platform 12 which carries the rolls and associated working portions of the mechanism. The rolls 13 in the embodiment shown are four in number and are equally spaced from one another with their axes in parallel relation to the center axis of the machine which is coincident with the axis of the tube T to be reduced and straightened. Although the four rolls are preferred, a greater or lesser number may be employed, and it is not the intention to limit the invention to that number of rolls unless otherwise indicated in the claims. From each of the rolls extends a left-end reduced axle section 14 and a similar right end axle section 15, which sections are surrounded by thrust ball-bearings 16 and 17 respectively.

The left-end axle section 14 of each roll carries a sprocket 18 which is keyed thereto, but aside from the presence of said sprocket, the mountings for the rolls are uniform at each end so that a description for one will suffice for both. The reduced axle section of each roll at each end is journaled within an adjustable journal block 19 which has an adjusting stem 20 threaded thereto which stem is entered between hardened spacer plates 21 and through an over-hanging flange 22 and is threaded at its outer end 23 to receive a nut 24 which permits the journal block to be moved radially to the degree necessary to uniformly adjust the acting surfaces of the rolls comprising the group to the required distance from the axis A and when adjusted to the desired extent permits the journal blocks to be clamped tightly against the hardened spacer plates 21 so that the hardened plates will resist the thrust of the rolls when exerting a reducing and straightening pressure upon the wall of the tube.

The over-hanging flange 22 extends continuously around the periphery of a rugged, integral frame 25 which, as shown in Fig. 1, is of generally octagonal shape presenting flattened corners 26 which provide for the mounting of the adjusting stems 20, the rolls occupying the corner positions with relation to the frame 25.

Each of the journal blocks 19 rides within a radially extending rectangular recess 27 open toward the center which, as shown in Fig. 4, is defined by an inwardly extending marginal flange 28 which extends continuously around the inner margins of the recesses which in unison present the star-shaped configuration shown, and the marginal flanges toward the outer end of each recess unite in a widened floor section 29 giving to this portion of the structure an arch-shaped configuration which affords clearance for the front and rear axle sections of the respective rolls.

The journal blocks abut against the inwardly protruding marginal flanges 28 and are held in place by inwardly tapering clamping plates 30 arranged to present their edges in substantially aligned relation to the flanges so that guide faces are provided for the in-and-out adjustment of the journal blocks. The clamping plates are held in position by screws 31 which permit their easy removal as occasion may require.

The frame 25 at its base merges into a base plate 32 and at its inner edge is extended laterally to provide side wings 33 which receive thru bolts 34 running between the front and rear frames,

which bolts are reduced and shouldered and threaded at their ends to receive nuts 36 which thus serve to rigidly unite the front and rear frame sections into a unified frame supported upon the platform 12 by bolts 37.

The rolls 13, which more particularly form the subject matter of the present invention, are each provided with a continuous spirally extending rib or thread 38, the convolutions of which at the intake end of the roll are of inwardly increasing diameter and with rounded contacting edges 39 giving to this portion of the acting surface of the roll a slightly tapered configuration which gradually reduces the clearance space between the rolls for about half the distance traversed by the tube in passing through the machine. This right-hand portion of each of the rolls may properly be termed the reducing section which imparts a slight reduction to the diameter of the tube and serves to feed the tube forwardly by a screw action as the rolls are rotated in unison in a manner presently to be described.

It will be noted, moreover, that the convolutions of the spiral thread or rib are spaced from one another by intervening gape or valleys, so that at any given instant, each roll will contact the tube wall along a longitudinal line of separated points with intervening clearances which permit the fibers of the metal to flow or readjust themselves during the reducing operation and prevent excessive frictional contact which would interfere with said flow and readjustment and would tend to result in a galling or abrasion of the tube surface which is avoided by imparting the compressive stresses at separated points in the manner stated. It will, of course, be understood that as the tube advances, and is subjected to rotation, each point of contact will become a constituent of a spirally extending continuous line which is the resultant of the application of the radially directed pressure against the surface of a rotating and constantly advancing tube wall and which will tend to impart a slight spiral grooving to the tube surface which, however, is flattened down or largely obliterated by reason of the fact that the convolutions in the respective rolls are stepped or staggered so that they will not track or follow in the same line with one another.

Thus, as seen in Fig. 3, the crests of the upper convolutions stand opposite the gaps or valleys of the lower convolutions while the intermediate rolls will respectively measure off one-fourth and three-fourths of the distance so that the four rolls, acting in unison, in conjunction with the advancement of the tube itself, due to the forward feeding action of the screw threads, will in a large measure, if not entirely, break up any continuity in the formation of spiral grooves 1 on the surface of the tube. At the same time the spacing of the points of contact, with the provision of intermediate gaps, as the tube is forced progressively through a contracting clearance space, will in unison rework and compact the fibers of the metal in such a way as to work out and obliterate any inequalities in the diameter of the tube and newly displace and compress the fibers so that when the tube emerges from the machine, it will not only be of truly circular section but will be toughened and hardened to a substantial degree.

Although the reducing ends of the rolls produce the result above specified, it is desirable to additionally straighten and iron out the surface by passing it through the terminal sections of the

rolls which are of truly cylindrical contour along the acting surfaces of the threads, the crests of which throughout the straightening portions of the rolls, are flattened as at 40 so that each crest presents a line contact, rather than a point contact with the tube surface, which contact lines as the tube is rotated will become the constituents of relatively broad spiral bands or stripes as distinguished from the spiral lines which are the resultant of the contacts provided by the rounded convolutions in the reducing portions of the roll structure. Since the roll surfaces throughout the straightening sections of the rolls maintain an equal spacing throughout from the axis of the tube, and since the convolutions of the respective rolls are stepped or staggered in the manner previously mentioned, it is evident that during the passage of the tube through the straightening section of the machine, any remaining inequalities in the surface will be smoothed down or ironed out so that the tube when delivered will present a smooth, even, and truly cylindrical surface from end to end.

Suitable means are provided for uniformly driving all of the rolls from a single source of power, and mechanism for performing this result is shown in detail in Fig. 1 although it will be understood that other equivalent means may be employed for obtaining this result.

As shown, all of the sprockets 18 are encircled by an endless sprocket chain 41 which embraces each of the sprockets in sufficient degree to engage several of the sprocket teeth; and in order to maintain such engagement, the opposite turns 35 of the sprocket chains are carried inside of similarly spaced idler sprockets 42 carried by stub shafts 43 below which the sprocket chain is carried around a centrally disposed driving sprocket 44 keyed upon a horizontal transmission shaft 45 carrying a worm gear 46 which meshes with a worm 47 on a worm shaft 48, which in turn carries a pulley 49 driven by a belt 50 carried around pulley 51 on a motor shaft 52 which is driven by a motor 53 mounted upon a slide 54 adjustably supported upon a plate 55 carried by the base frame 10 permitting fore-and-aft adjustment.

In order to provide for the taking up or releasing of slack in the sprocket chain, due to the radial adjustment of the rolls to accommodate tubing of different diameters, the driving sprocket 44 and parts carried thereby are vertically adjustable as indicated in Figs. 1 and 2.

To provide for such adjustment the shaft 45 is surrounded by bushings 56 and 56a which are carried by a journal mounting 57 comprising forward and rear sections 58 and 59 which are recessed on their inner faces 60 and 61 respectively to provide a chamber for the worm gear 46 and the worm 47. The two sections are united by bolts 62, and the bushing 56a is socketed within a recess 63 in an extension 64 from the section 58, which arrangement provides an extended journal for the shaft 45. The journal mounting is provided on each side with fins 65 which travel within guide slots 66 and over-lying plates 67 secured by bolts 68 to the forward frame plate 11, which fins are of sufficient length to afford an extended slide mounting to prevent cramping or binding under the preponderance of weight on the rear side of the forward frame plate.

Vertical adjustment is afforded by a screw 69 which is provided at its upper end with a smooth stem 70 passing through a lug 71 on the forward section of the mounting 57, the stem terminating

in a reduced and threaded extension 72, carrying a nut 73 which coacts with a hexagonal flat-faced portion 74 on the lower side of the lug in affording a journal mounting for the screw which permits a wrench to be applied to the flat-faced collar to rotate the screw. The lower end of the screw is threaded into a post 75 shouldered and bolted to the forward edge of the base frame 10 immediately in advance of an arched opening 76 in the forward frame plate which affords clearance for the vertical movements of the journal mounting and for the location of the screw and associated parts.

In order to take up or release slack in the motor belt 50, occasioned by the vertical adjustments of the journal mounting 51, an adjustment screw 77 is provided, the forward end of which is journaled within an angle-shaped bracket 78 carried by the floor plate 55, and the rear threaded end of which is entered through a lug 79 on the base plate 54 of the motor which affords limited longitudinal adjustment to the motor as occasion may require.

Variable speeds may be imparted to the motor through the provision of an adjustable switch 80 of any suitable character.

Operation

In operation, the rolls are equally adjusted in order to bring their acting surfaces to an equal distance from the axial center of the clearance space through which the tubing is intended to travel, which clearance space should be sufficient to permit the forward end of the unreduced tube section to be entered between the rear ends of the rolls and in contact with the rounded edges of the first convolution of each of the rolls. Thereafter as the rolls are rotated they will exert a screw-feeding action on the tube which will be rotated by the bite of the rolls as its advancement begins. The gradual progressive increase in the diameter of the convolutions will correspondingly decrease the clearance space so that as the tube section advances, it will be gradually reduced in sufficient amount to rework the metallic fibers of the tube wall, thereby eliminating the previous set of the fibers and working out any inequalities in the circularity of the tube.

At the same time the method of applying the reducing pressures at equal distances on different sides of the tube and in radially opposed directions to one another will accurately center the tube so that its axis will exactly coincide with the axis of the clearance space. The spacing of the convolutions serves to apply the reducing pressures at any instant along aligned points extending longitudinally of the tube surface so that the reducing stresses at any instant will be applied to minute areas of the tube surface rather than along continuous lines of contact, thereby affording opportunity for a redistribution of the metal fibers as the reducing operation progresses. While a single convoluted reducing roll might cause the formation of spiral grooves in the tube surface, the provision of a group of rolls, preferably not less than three in number, and with the convolutions progressively staggered, will substantially smooth out and obliterate any perceptible grooving so that as the tube passes through the flat-edged terminal convolutions, its surface will be ironed out and subjected throughout a considerable extent to a uniform smoothing operation which gives to the tube the final smoothing and centering effect required.

Although the present method requires a preliminary slight reduction in the tube diameter, this reducing operation is performed primarily for the purpose of reworking the metal fibers to eliminate inequalities and to strengthen and toughen the metal, and the reducing is therefore to be regarded as preliminary to the straightening operation, and as incidental thereto and in most, if not all, cases the reduction will proceed by gradual stages and only to the degree necessary to effectively rework the metal in preparation for the ultimate smoothing and straightening operation performed by the terminal portions of the rolls.

15 In the reducing operation, there will be either a slight elongation of the tube or a possible slight thickening of the tube walls, or both of these effects may occur, but such results are slight in degree and are to be regarded as merely incidental to the straightening operation previously described.

Although the invention has been described with particularity as to detail, it is not intended, unless otherwise indicated in the claims, to limit the construction to the number of rolls shown or to the herein described method of mounting and driving the rolls, since modifications in these details may be made without departing from the spirit of the invention.

30 Although in the embodiment shown the forward feeding of the tube is occasioned by the screw action of the convolute ribs without the employment of additional feeding force, it is to be understood that on occasion it may be desirable to supplement the screw feeding action by the employment of any suitable means of a character well understood in the art.

I claim:

1. The method of straightening tubing which 40 consists in applying reducing pressures with blunt edged ribs against different faces of the tube wall and directed inwardly radially toward the axis of the tubing, said pressures being applied at any instant in slightly converging lines of separated 45 points, said points moving longitudinally of the tube wall and being the constituents of rotating and spirally moving continuous lines of reducing pressure contact, progressively and in equal degree approaching the axis of the tubing while undergoing relative rotation and relative linear advancement, and by progressive reduction, reworking the metal fibers of the tubing, and after such 50 reduction subjecting the tube wall to straightening pressures with ribs flat in transverse cross-section directed inwardly radially toward different faces of the tube wall and being applied at any given instant in parallel lines of separated contacts equally spaced throughout from the axis of the tubing, and being the constituents of rotating 55 and spirally moving planes of straightening pressure contact and serving to subject the tube wall to a smoothing and straightening operation.

2. The method of straightening tubing which 60 consists in applying reducing pressures with blunt edged ribs against different faces of the tube wall and directed inwardly radially toward the axis of the tubing, said pressures being applied at any instant in slightly converging lines of separated 65 points, said points advancing longitudinally of the tube wall and being the constituents of not less than three rotating and spirally advancing continuous non-tracking lines of reducing pressure contact, progressively and in equal degree approaching the axis of the tubing while undergoing relative rotation and relative linear advance-

ment, and by progressive reduction, reworking the metal fibers of the tubing, and after such reduction subjecting the tube wall to straightening pressures with ribs flat in transverse cross-section directed inwardly radially toward different faces of the tube wall and being applied at any given instant in parallel lines of separated contacts equally spaced throughout from the axis of the tubing, and being the constituents of not less than three rotating and spirally advancing planes of straightening pressure contact and serving to subject the tube wall to a smoothing and straightening operation, the separated straightening contacts being longitudinally extended as line pressures to span, at any given instant a substantial extent of the tube surface.

3. The method of straightening tubing which consists in applying reducing pressures with blunt edged ribs against different faces of the tube wall and directed inwardly radially toward the axis of the tubing, said pressures being applied at any instant in slightly converging lines of separated points, said points advancing longitudinally of the tube wall and being the constituents of not less than three rotating and spirally advancing continuous non-tracking lines of reducing pressure contact, progressively and in equal degree approaching the axis of the tubing while undergoing relative rotation and relative linear advancement, and by progressive reduction, reworking the metal fibers of the tubing, and after such reduction subjecting the tube wall to straightening pressures with ribs flat in transverse cross-section directed inwardly radially toward different faces of the tube wall and being applied at any given instant in not less than three parallel lines of separated contacts equally spaced throughout from the axis of the tubing, and being the constituents of rotating and spirally advancing non-tracking continuous planes of straightening pressure contact and serving to subject the tube wall to a smoothing and straightening operation, the rotating and spirally advancing lines of straightening pressure contact being uninterrupted con-

tinuations of the rotating and spirally advancing lines of reducing pressure contact.

4. The method of straightening tubing which consists in applying reducing pressures with blunt edged ribs against different faces of the tube wall and directed inwardly radially toward the axis of the tubing, said pressures being applied at any instant in not less than three slightly converging lines of separated points, said points advancing longitudinally of the tube wall and being the constituents of rotating and spirally advancing non-tracking continuous lines of reducing pressure contact, progressively and in equal degree approaching the axis of the tubing while undergoing relative rotation and relative linear advancement, and by progressive reduction, reworking the metal fibers of the tubing, and after such reduction subjecting the tube wall to straightening pressures with ribs flat in transverse cross-section directed inwardly radially toward not less than three different faces of the tube wall and being applied at any given instant in parallel lines of separated contacts substantially equally spaced throughout from the axis of the tubing, and being the constituents of rotating and spirally advancing non-tracking continuous planes of straightening pressure contact and serving to subject the tube wall to a smoothing and straightening operation, the separated straightening contacts being longitudinally extended as line pressures to span, at any given instant a substantial extent of the tube surface, the rotating and spirally advancing lines of straightening pressure contact being uninterrupted continuations of the rotating and spirally advancing lines of reducing pressure contact.

5. Apparatus for straightening tubing including a roll having a generally helical blunt-edged rib of gradually increasing diameter to effect a slight degree of reduction, the terminal portions 40 of said rib means being flat-faced in cross-section a. continuous uniform diameter to effect a smoothing operation after the tube has been slightly reduced.

CLARENCE L. DEWEY.
